DESIGN FOR A SHIELD

Holger Pedersen, New York, N. Y.

Application March 22, 1945, Serial No. 118,631

Term of patent 7 years

(Cl. D29—2)

To all whom it may concern:

Be it known that I, Holger Pedersen, residing at New York, in the county of New York and State of New York, have invented a new, original, and ornamental Design for a Shield, of which the following is a specification, reference being had to the accompanying drawing, forming part thereof.

The figure is a front view partially in perspec-

tive of a shield embodying my new design, with the second small shield fragmentarily shown for convenience of illustration.

I claim:

The ornamental design for a shield, as shown and described.

HOLGER PEDERSEN.
